E. G. LOOMIS.

DEVICE FOR INSERTING CRYSTALS IN BEZELS AND RINGS.

APPLICATION FILED NOV. 25, 1918.

1,344,700

Patented June 29, 1920.

UNITED STATES PATENT OFFICE.

EVARTS G. LOOMIS, OF NEWARK, NEW JERSEY.

DEVICE FOR INSERTING CRYSTALS IN BEZELS AND RINGS.

1,344,700.

Specification of Letters Patent. Patented June 29, 1920.

Application filed November 25, 1918. Serial No. 264,036.

To all whom it may concern:

Be it known that I, EVARTS G. LOOMIS, a citizen of the United States, and a resident of Newark, county of Essex, and State of New Jersey, have invented certain new and useful Improvements Relating to Devices for Inserting Crystals in Bezels and Rings, of which the following is a specification.

- 10 This invention relates to a device for inserting thin resilient disks in watch bezels or in grooved rings. It relates particularly to the insertion in watch bezels of unbreakable concavo-convex tensional crystals, of 15 the kind disclosed in the Ames Patent No. 1,133,780, issued March 30, 1915. A crystal of this type is made of a resilient disk of transparent celluloid or similar material, of a diameter substantially greater than that 20 of the bezel-groove which it is to occupy, the disk being held by the bezel in concavo-convex form, under tension, when the structure is assembled. The disk accordingly requires to be thrown into precise dished condition, and while in this form and tensioned, its flexible edge must be brought within the small bezel-groove in order that it may seat itself circumferentially therein upon the removal of the temporary holding forces. 25 One of the objects of the present invention is to provide means whereby these operations can be performed quickly and effectively.

Other objects of the invention will appear 30 from the detailed description and from the drawings, forming a part of this specification, in which—

Figure 1 is a side elevation, partly in section, of the preferred embodiment of the 35 device, the device being shown open with a crystal disk in waiting position, and a bezel carried upon a centering surface;

Fig. 2 is a rear elevation of the device;

Fig. 3 is a fragmentary sectional view, 40 showing the device closed and flexing the crystal, the bezel being in receiving position;

Fig. 4 is an elevation of another form of male member; and

50 Fig. 5 is an elevation of still another form of male member.

As illustrated, the device comprises a stand 1 having a central base 2, provided with screw holes 3, for securing the same to 55 a table, a short standard 4, and widely-di-

verging yoke-arms 5 and 6; the whole being preferably of approximate Y-shape, as shown.

The arm 5 has a horizontal inwardly-facing socket 7, which receives a stem 8, projecting from a female pressure-member 9, preferably formed in this instance of a short cylindrical block having a central opening 10 therethrough, whereby the block may be applied and frictionally and removably held upon an extension 11 of said stem, against the collar or abutment 12. The stem in rear of said collar is formed as a journal capable of turning within the socket 7 as a bearing, a thrust ball 13 being placed between the end of the journal and the back of the socket. A radial set-screw 14 is inserted in the socket wall with its extremity projecting into a circumferential groove 15 in the stem 8 to hold the same against withdrawal.

The other arm 6 is made with a horizontal through-opening 16, which is screw-threaded and alined with the socket 7. This opening receives a pressure screw 17 carrying a hand-wheel 18 at its outer end, the inner end of the screw being formed with a bearing-socket 19 containing a thrust ball 20 and a journal stem 21 pertaining to a male pressure-member 22. As in the case of the female member 9, the said stem 21 is provided with an extension 23 and a collar 24. Upon the extension 23 is removably mounted a male member 22 which has a central bore 25 for receiving the extension 23.

The member 9, it will be observed, is formed upon its inner end face with a circular shallow concavity or female pressure surface 26, which curves equally in all directions from the center to the face of the block. The annular rim 31 surrounding the concave depression 26 in the block 9 will serve as an abutment, as will hereinafter appear. The male member 22, on the contrary, is made of smaller diameter, with its entire end face 27 of convex formation corresponding substantially to the concavity of the female member, so that a crystal disk *a* placed between them will be flexed from the flat initial condition of Fig. 1 to the uniformly bowed-shape indicated in Fig. 3, this change reducing the diameter of the disk and placing it under tension, by virtue of which it tends to resume its original form.

The cylindrical surface 28 of the male 110

member is designed to form a centering guide and carrier for the bezel *b*, the diameter of said surface being accordingly made to receive the bezel with a substantially accurate sliding fit. A ring 29, also slideable on said surface 28, serves as a follower, whereby the bezel may be held evenly against the abutment 31 on the female member 9 when the parts are in the closed position of Fig. 10 3. At such time the front of the bezel will bear against the female member at or adjacent the edge of the concavity 26, or else the back of its groove may contact with the edge of the crystal, depending somewhat 15 upon the precise form and proportions of the bezel and crystal, but in either event the support limiting the forward movement of the bezel to a position insuring reception of the crystal is afforded by the female 20 member.

In operation, with the parts separated in the manner seen in Fig. 1, a disk *a* is placed and held by hand with its beveled edge in the mouth of the concavity 26, which is 25 made of proper diameter for this purpose and which accordingly serves to center the disk with respect to the pressure surfaces and the bezel. A bezel having been slipped over the male member 22 in front of the 30 follower 29, the said member is then advanced by means of the hand-wheel and screw until the convex face of the male member is brought against the disk, which is then flexed into the concavity of the female 35 member and thereby tensioned as previously stated. At this time the bezel is pushed forward by the ring 29 in the manner above described. In so doing the forward edge of its undercut groove does not encounter 40 the beveled edge of the crystal because of the virtual reduction in the diameter of the latter, and the bezel is thus disposed in a receptive position around the crystal which will seat itself as soon as the tension is 45 removed. Accordingly the operator continues, with the fingers of one hand and preferably through the agency of the follower ring, to hold the bezel against the abutment 31 on the female member, while 50 with the other hand he backs up the male member 22 sufficiently to permit the crystal to slip into firmly-seated engagement with the bezel-groove. The male member is then withdrawn farther by the screw means 17, 55 the assembled bezel and crystal are taken off, and the ring 29 is pushed back in readiness for another bezel. The swiveled mounting of the female member is desirable in connection with the centering of the parts, 60 and the swivel connection between the male member and the pressure screw enables this member to be independent of the turning movement of the screw.

It will be understood that various male 65 and female members differing in form and

proportions may be used interchangeably. Fig. 4 shows a form of male member 22^a, the bezel-centering surface 28^a having the rear portion cut away or relieved, this style of member being suitable for bezels which are 70 hinged to their watch cases. Fig. 5 illustrates still another form of male member 22^b, which is formed with a rear rim 30 to prevent the bezel from slipping off at the back. Portions of these members corresponding to similar portions of the member shown in Fig. 1 bear the same reference numerals, with super characters "a" and "b" respectively. If desired, either of the two alternative forms may be used with 80 the ring 29.

It is to be understood that various changes may be made in the details of construction herein illustrated and described within the purview of this invention. 85

What I claim is:

1. A device for assembling bezels or grooved rings with tensional crystals comprising horizontally disposed relatively movable members affording concave and convex pressure surfaces coöperating to throw the crystals into tension and reduce their virtual diameter, one member sustaining and guiding the bezel or ring into crystal-receiving position and the other member 95 being of larger diameter than the first-mentioned member to limit the movement of the bezel or ring into crystal-receiving position.

2. A device for assembling bezels or grooved rings with tensional crystals, comprising horizontally disposed relatively movable male and female members affording concave and convex pressure surfaces co-operating to throw the crystals into tension and reduce its virtual diameter, the male 100 member sustaining and guiding the bezel or ring into crystal-receiving position, and the female member being of larger diameter than the male member and limiting the movement of the bezel or ring in a forward 105 direction when the said bezel or ring is in crystal-receiving position.

3. A device for assembling bezels or grooved rings with tensional unbreakable crystals comprising a stand, coöperating 115 pressure elements, one of which receives the crystal and the other of which supports the bezel or ring, means for advancing and retracting one member into and out of engagement with the crystal, and swiveled mountings for both members.

4. A device for assembling bezels or grooved rings with tensional unbreakable crystals, comprising a stand, male and female members thereon for flexing the 125 crystal into concavo-convex form, means for advancing and retracting the male member, means for positioning the bezel or ring, and a swivel mounting for said female member.

5. A device for assembling bezels or 130

- grooved rings with tensional crystals, comprising a stand, a female member for receiving the crystal, a male member for supporting the bezel or ring, the male and female members being supported by the stand in horizontal position, means for advancing and retracting the male member into and out of engagement with the crystal, and swivel mountings for said male and female members.
6. A device for assembling bezels or grooved rings with tensional crystals comprising a stand, a crystal-receiving member, a bezel-receiving member in alinement with the first-named member, said members being supported by the stand in horizontal position, swiveled mountings and thrust bearings for said members, and means for moving one member into engagement with the crystal to place the same under tension and maintain it in position to receive the bezel.
7. A device for assembling bezels or grooved rings with tensional crystals, comprising a stand, a crystal-receiving female member, a male member in alinement with said female member for receiving the bezel
- or grooved ring, the male and female members being supported by the stand in horizontal position, swivel mountings and thrust bearings for said male and female members, and means for moving said male member into engagement with the crystal to place the same under tension and maintain it in position to receive the bezel.
8. A device for assembling bezels or grooved rings with tensional crystals, comprising a stand, a female member for receiving the crystal, a swivel mounting for supporting the female member on the stand, a male member for supporting the bezel or ring, a swivel mounting for said member, and a member having screw-threaded connection with the stand for advancing and retracting the male member into and out of engagement with the crystal.

This specification signed and witnessed this 22nd day of November, A. D. 1918.

EVARTS G. LOOMIS.
